TAP BUSH AND METHOD OF FORMING
THE SAME

Claude Sintz, Detroit, Mich.

Application October 16, 1933, Serial No. 693,843

6 Claims. (Cl. 29—148.2)

The invention relates to tap bushes of the standard type used in connection with beer barrels and more particularly those used upon metallic barrels. It is the object of the invention to obtain a construction which has greater strength to withstand the stresses to which such bushes are subjected and to this end the invention consists, first, in the method of constructing the bush, and second, in the improved product resulting from this method.

In the drawing:

Fig. 1 is a plan view partly in section of my improved tap bush;

Fig. 2 is a cross section therethrough;

Fig. 3 is a plan view of the sleeve for forming the switch;

Fig. 4 is a vertical central section illustrating the manner of extruding the teeth on the bush body;

Fig. 5 is a section illustrating the manner of engaging the switch sleeve with the body of the bush;

Fig. 6 is a side elevation of Fig. 3.

In the present state of the art, the standard construction of tap bush comprises the following elements: A circular body A is adapted to be peripherally welded to the outer wall B and the inner wall C of a metallic beer barrel. D is a central aperture for receiving the discharge pipe and E is the so-called switch surrounding the central aperture and which consists of a tubular portion E' and an outwardly projecting flange E² having a spiral cam on its under face. Between this switch and the outer portion of the bush is an annular recess F for receiving the so-called nugget of the tap which cooperates with the switch to secure the discharge pipe to the barrel. Also the upper face of the switch forms a seat for a gasket that forms the seal between the pipe and the bush.

As has been stated, the bush above described is of standard form and dimensions which can not be altered without rendering the structure inoperative for general use with beer taps. The structure is, however, one which is difficult to manufacture, for the spiral cam can not be conveniently formed integral with the body of the bush. On the other hand, where the switch is formed separate from the body of the bush and attached thereto by welding, the strength of the structure is greatly impaired. Thus in use and particularly by reason of the abuse to which such fittings are subjected, the switch is frequently broken off, thereby destroying the structure.

With the present invention I obtain a construc-

tion of tap bush in which the spiral flange or cam portion of the switch is originally formed on a sleeve F', the inner face of which is provided with longitudinal serrations G while the body portion of the bush has formed integral therewith a central tube H externally serrated at I to engage the serrations of the sleeve. In order, however, to provide the necessary strength, these serrations on the central tube are not machined but are formed by extrusion under heavy pressure. Also the sleeve F' is securely attached to the tube H by an extension of the latter, which is pressed outward or riveted over the sleeve engaging a beveled recess therein.

In the process of manufacture, the body of the tap bush including the central tube H is formed of a steel forging which is machined to accurate dimensions. The sleeve F' together with the spiral flange E², is formed of a separate steel forging, the external surface of which may be fashioned in a die while the interior surface is broached to form the serrations G.

After the machining of the body of the bush, it is subjected to the extruding operation as follows: The extruding die J is of tubular form and has on the lower portion of its inner face a series of teeth K for fitting in the serrations G of the sleeve F'. Above the serrated portion of the die is a cylindrical portion L for fitting a portion of a core or pilot member M. This member is cut away at N opposite the serrated portion of the die J while below the cut-away portion is a portion O for fitting the inner surface of the tube H and sustaining the same during the extruding operation. The member M has a head P for engaging a recess or counterbore Q in the die J so that when the members J and M are placed together they are held in concentric relation and from any longitudinal displacement.

The extruding operation is performed by placing the body portion of the bush in a suitable holder and in registration with the die J and by then pressing said die, together with the member M, downward. During this operation the pilot O which is in advance of the die, will enter the tube H and hold it from being crushed inward so that the teeth K will press into the outer wall of the tube and cause the metal thereof to flow outward into the spaces or serrations between said teeth. The original outer diameter of the tube H is such that the amount of metal which is displaced by pressing the teeth K therein, equals the amount of metal required to fill the serrations, so that in the completed structure there is the same amount of metal as in the tube before

the operation. Furthermore, the enormous pressure to which the metal is subjected will have a densifying effect, imparting a strength thereto which is greatly in excess of that of a similar structure formed by machining.

5 After the completion of this extruding operation, the sleeve F is pressed on the tube H, after which the end portion H' of the tube is upset to fill a V-shaped recess H² in the upper end 10 of the sleeve and to form a head which will prevent disengagement.

15 With a tap bush formed as described, the switch is held from rotation on the body by the serrations and is also held from longitudinal displacement by the upset head on the tube H.

20 The head H' engaging the recess H² brings the joint between the members at a point where it will be under the sealing portion of the gasket. Consequently if there should be any leakage of gas between the two members, this will be stopped by the gasket.

What I claim as my invention is:

25 1. A tap bush comprising a body having a central tubular stem with externally projecting teeth of high density and strength such as is characteristic of extruded metal and a switch formed of a sleeve surrounding said tubular stem and having internal serrations for engaging said teeth.

30 2. A tap bush comprising a body having a central tubular stem provided with externally projecting teeth of high density and strength such as is characteristic of extruded metal, a switch formed of a sleeve surrounding said stem and 35 having internal serrations for engaging said teeth, the outer end of said tubular stem being headed to retain said sleeve from disengagement.

35 3. A tap bush comprising a body having a central tubular stem with externally projecting teeth of high density and strength such as is characteristic of extruded metal, a switch formed of a sleeve surrounding said tubular stem and internally serrated to engage said teeth, said sleeve having a recess in its outer end, and the outer

end of said tubular stem being headed to fill said recess.

4. The method of forming tap bushes which consists in separately forging the body portion of the bush and a switch therefor, said body portion being provided with a central tubular stem and said switch being integral with a sleeve for surrounding said stem having internal longitudinally extending serrations, extruding said tubular stem to form outwardly extending teeth 10 for engaging and fitting said serrations, and pressing said switch upon said body portion.

5. The method of forming tap bushes which consists in separately forging the body portion of the bush and the switch portion thereof, said body portion being provided with a central tubular stem and said switch being integral with a sleeve for surrounding said stem, internally broaching said sleeve to form a series of longitudinally extending serrations, extruding said tubular stem 20 to form externally projecting teeth for engaging said serrations, pressing said switch upon said body portion and heading the outer end of said tubular stem over said sleeve.

25 6. The method of forming tap bushes which consists in separately forging the body portion of the bush and the switch portion thereof, said body portion being provided with an integral central tubular stem and said switch being integral with a sleeve for surrounding said stem, internally broaching said sleeve to form a series of longitudinally extending serrations therein, externally machining said tubular stem to a diameter in excess of the inner diameter of the serrations of said sleeve but less than the outer diameter of said serrations, engaging said tubular stem with an extruding die fashioned to form teeth 30 for engaging the serrations of said sleeve whereby the metal displaced by the inward projection of the die teeth will flow outward to fill the 35 interstices of said die, and pressing said switch upon said body portion.
